UNITED STATES PATENT OFFICE.

FRANCIS H. YOUNG, OF HOBOKEN, NEW JERSEY.

ROLLER-BEARING AND LUBRICATOR.

SPECIFICATION forming part of Letters Patent No. 678,089, dated July 9, 1901.

Application filed September 4, 1900. Serial No. 28,878. (No model.)

To all whom it may concern:

Be it known that I, FRANCIS H. YOUNG, a citizen of the United States, residing at Hoboken, in the county of Hudson and State of New Jersey, have invented certain new and useful Improvements in Roller-Bearings and Lubricators, of which the following is a full and complete specification, such as will enable those skilled in the art to which it appertains to make and use the same.

This invention relates to journal-bearings for railway-cars; and the object thereof is to provide an improved bearing of this class and means for automatically oiling or lubricating the journals thereof; and with this and other objects in view the invention consists in the construction, combination, and arrangement of parts hereinafter described and claimed.

The invention is fully disclosed in the following specification, of which the accompanying drawings form a part, in which the separate parts of my improvement are designated by the same reference characters in each of the views, and in which—

Figure 1 is an outside view of an ordinary journal-box provided with my improved bearing, the front wall of the box or casing being removed; Fig. 2, a transverse vertical section thereof on the line 2 2 of Fig. 3; Fig. 3, a central vertical section at right angles to the section shown in Fig. 2, taken on the line 3 3 of Fig. 1; and Fig. 4, a perspective view of a bearing-frame which I employ, said frame being composed of separate parts, which are shown detached in this figure.

In the drawings forming part of this specification I have shown at *a* an ordinary journal box or casing such as is usually employed for inclosing bearings of the class specified, and this box or casing may be of any desired construction. The said box or casing *a* is provided with a rear wall *a*², through which the car-axle *b* passes, and the said axle *b* is provided with the usual journal *b*², the end of which is provided with a circular head *b*³.

Mounted in the top of the box or casing *a*² is a journal-bearing frame *c*, in which are placed two rollers *d*, each of which is provided at each end with a journal *d*², and the journals *d*² fit in small journal-boxes *d*³, set into the opposite sides of the bearing-frame.

The bearing-frame *c* or the side thereof adjacent to the rear wall *a*² of the box or casing *a* is cut out segmentally, as shown at *c*², to 55 form a space in which the axle *b* works, and the front wall of the said bearing-frame *c* is similarly cut out, as shown at *c*³, to form a space in which the head *b*³ of the journal *b*² works. The rollers *d* are much greater in diameter than the journal *b*² and are substantially of the same length as said journal and fit between the head *b*³ thereof and the annular shoulder *b*⁴ at the inner end of said journal, and the entire weight borne by the journal is placed upon the bearing-frame *c*, which is supported by the rollers *d* on said journal, and any lateral movement of the journal or of the rollers *d* is prevented by the head *b*³ of the journal and the annular shoulder *b*⁴ at the 65 inner end thereof, said parts operating against the opposite ends of said rollers in order to accomplish this result, as will be readily understood.

Mounted in the bottom of the box or casing *a* is a float comprising a frame *e*, composed of any desired material, and in which is revolubly supported a float-roller *g*, which is adapted to turn in its bearings *h*, and said roller *g* may be composed of any desired material, and, as shown in the drawings, is made hollow, and the length thereof is substantially equal to the length of the journal *b*² between the head *b*³ thereof and the annular shoulder *b*⁴. The float-frame *e* may also be 85 made of any desired material, and in practice the bottom of the box or casing *a* is partially filled with oil or any suitable lubricating material, as shown at *k* in Fig. 2, and in the operation of the apparatus the cylindrical and 90 revoluble float-roller *g* is always held in contact with the journal *b*² and is constantly revolved thereby, and said journal is thus kept constantly lubricated, and the rollers *d* coming in contact with said journal are also constantly lubricated.

The bearing-frame *c* is composed of two separate parts, as shown in Fig. 4, in order to facilitate the placing of the rollers *d* therein for the purpose of renewing said rollers when 100 necessary, and in making said bearing-frame *c* I preferably divide the opposite sides thereof centrally, as shown at *m*, and form the separate parts so that they will overlap, as

shown at *n*, and the separate parts of the bearing are secured together by rivets, bolts, or other devices *o*, as shown in Fig. 2.

It will be observed that the bearing-frame *c* is divided transversely of the rollers hinged therein, and by reason of this construction the said rollers may be detached or placed in position or renewed whenever desired, and in order to accomplish this object the separate parts of the bearing-frame are in practice preferably connected by rivets.

The bearing-rollers *d* may be made of any desired diameter and are preferably made from two to three times the diameter of the journal *b*², and by means of my improved construction I provide a journal - bearing which is perfectly lubricated at all times, and which is also strong and durable and by means of which friction in operation is reduced to a minimum.

The frame *c* is supported or steadied by the diamond frame now in use. The box or casing *a* is in practice slipped on over the spindle or journal of the axle, and the frame *c*, with the rollers *d* mounted therein, is then placed in position on the top of the journal or spindle inside of the box or casing *a*, the box or casing *a* being open at the top and provided with castings or supports for the diamond frame referred to, and the parts are all bolted together in the usual manner.

By making the frame *c* of two parts I provide means whereby repairs may be made to the journals of a car or the bearings thereof without taking the car to the general shops of the road, it being understood that new bearing-rollers may be put in this frame *c* wherever and whenever necessary, whereas if the frames were made integrally it would be impossible to make repairs without taking the car to the shop. It will also be apparent that by making the bearing-rollers in the frame *c* of greater diameter than the journal

of the axle less friction and less heat will be generated, as it will be necessary for the bearing-rollers to turn a much less number of times than if they were of comparatively small size. Another advantage which I secure is by employing the float *e*, in which the lubricating-roller *g* is placed. By means of this construction I avoid the use of springs for supporting the float or frame of the roller *g* and at the same time prevent the slopping of the oil or other lubricant, the float, consisting of the frame and roller mounted therein, serving for this purpose.

Having fully described my invention, I claim as new and desire to secure by Letters Patent—

The combination with an axle having a journal provided with a circular head at its outer end, and an annular shoulder at its inner end, of a box or casing through the rear wall of which the journal passes, a floating frame mounted in the lower portion of the box and a cylinder carried by said floating frame and adapted to revolve in contact with said journal, and which is of the same length, and a bearing-frame mounted in the top of the box or casing and provided with two rollers of greater diameter than the journal and of the same length, the construction and arrangement being such that the said rollers operate between the head of said journal and the annular shoulder at the inner end thereof and fit between the same, substantially as shown and described.

In testimony that I claim the foregoing as my invention I have signed my name, in presence of the subscribing witnesses, this 31st day of August, 1900.

FRANCIS H. YOUNG.
